UNITED STATES PATENT OFFICE.

THEODORE H. WURMB AND ROBERT BAUMANN, OF ST. LOUIS, MISSOURI, ASSIGNEES
TO NATIONAL CLOCK & ELECTRIC MANUFACTURING CO., OF ST. LOUIS, MISSOURI,
A CORPORATION OF MISSOURI.

DESIGN FOR A THERMOMETER-CASING.

41,534.

Specification for Design.

Patented July 4, 1911.

Application filed August 29, 1910. Serial No. 579,617. Term of patent 14 years.

To all whom it may concern:

Be it known that we, THEODORE H. WURMB and ROBERT BAUMANN, citizens of the United States, residing at St. Louis, in the State of Missouri, have invented a new, original, and ornamental Design for Thermometer-Casings, of which the following is a specification, reference being had to the accompanying drawing, forming part thereof.

The figure is a perspective view of a thermometer casing, showing our new design.

We claim:

The ornamental design for a thermometer casing, as shown.

THEODORE H. WURMB.
ROBERT BAUMANN.

Witnesses:

E. L. WALLACE,
N. G. BUTLER.
